2,333,750

APPARATUS AND METHOD FOR APPLYING
GUMMED LABELS TO CELLOPHANE

John Kirby Tompkins, Narberth, Pa.

Application May 6, 1942, Serial No. 441,936

10 Claims. (Cl. 216—21)

My invention relates to the securement of water soluble gummed labels to Cellophane and like material in which heat and moisture are combined to effect the adhesion of the label to the Cellophane wrapper. Among the objects and purposes are to provide:

A wrapping of Cellophane or like material having a label secured thereto in which the adhesive is water soluble and which will not normally adhere to the Cellophane unless heat is combined with the moist adhesive.

A device for feeding labels and Cellophane and providing a moist water soluble adhesive and heating means to cause the water soluble gum to adhere to the Cellophane.

A device for moistening the surface of Cellophane or the like and the application of a label having water soluble adhesive and heat to secure the label to the Cellophane.

A method of securing labels with moist water soluble adhesive to Cellophane or like material by heat and pressure.

A rapid means of permanently securing labels to Cellophane by applying moist glue or water soluble gum and heat.

I accomplish these and other objects by the method, process and construction hereinafter specified and shown in the accompanying drawings forming a part hereof, in which:

Fig. 1 is a section and elevation showing the operation of my device.

Fig. 2 is a section and elevation of a modification.

Fig. 3 is a fragmentary section of a modification.

Fig. 4 is a fragmentary plan view.

Similar reference characters refer to similar parts throughout the several views of the drawings and in the specifications to follow.

The use of Cellophane and similar material for wrapping packages, foods, bread and cake has become nearly universal, and the securement of labels, seals, and the like, to this material, has presented a problem because only by the use of special adhesives such as rubber, and others equally expensive, or by slow methods, has the securement been possible.

In my application for Letters Patent titled Apparatus and method for applying gummed labels to Cellophane, filed April 3, 1942, Serial Number 437,476, I have disclosed a machine and process as well as a product of manufacture in which ordinary gummed labels (those having water soluble adhesive commonly used on labels) are secured to Cellophane wrappers.

In my application, Serial #437,476, I have shown means for moistening the gum or adhesive on the label which, because it is moist, in turn moistens the Cellophane at which time heat and pressure are applied to complete the securement.

In this instant patent application I have shown means for moistening the Cellophane direct or the moistening of the Cellophane by applying moist adhesive to labels as they are about to be contacted and heated in securing the labels to the Cellophane.

A label having any of the commonly used water soluble gums may be permanently secured to Cellophane or the like by moistening the gum and then, while moist, heating the label and pressing it onto the surface of the Cellophane.

The combining of moisture, heat and pressure to the label at the time of its application, insures its permanent adhesion to the Cellophane. The ordinary label thus will not peel off as it would if not moistened, or as it would if it were merely heated.

To facilitate these operations, I have provided a moistener to a machine which, in other respects, may be the same as now used in securing rubber coated labels to Cellophane. I do not wish to imply that other machines and attachments to machines cannot be made to work equally well using my invention in its simple broad concept, i. e. that of applying labels having ordinary water soluble gum to Cellophane, using moisture and heat.

Obviously, my apparatus for applying my process may be modified in numerous particulars without departing from the principles underlying my invention.

The product, as well as the machine and the process also is new and forms a part of my invention. A wrapper of Cellophane, in which the adhesive for the label is water soluble is, by the application of heat, forced to combine with the chemical elements of the Cellophane, thereby forming a bond with the adhesive and the label, to which the adhesive is secured and which may be paper or other material, is thus permanently secured to and forms a part of the wrapper.

Referring to the drawings, the frame 1 may be that of a machine for wrapping and labeling cakes, etc.; and in addition to the affixing of the labels 2, which are preferably in a continuous strip 3 and in a roll 4, is suited to feed and handle the cakes into the machine as well as to wrap each cake with a Cellophane wrapper to which has been secured the labels 2.

The machine may be constructed to slice the

cake and perform numerous operations in connection with the cake which are not necessarily dependent on the securing of the label to the Cellophane wrapper for the cake.

For the sake of brevity and clarity, I will describe in detail only the parts of the machine which cooperate to secure the label with its water soluble adhesive to the Cellophane. The parts, as well as the operations, may vary in their disposition to each other and to the machine as a whole, but are illustrative of the required principal operations to accomplish the function and result.

The roll 4 is preferably rotatably supported in relation to the machine or frame 1 and the continuous strip of labels is fed into the machine by the feed rolls 5 which control the tension, pressure and relation of the label strip.

In the modification shown in Fig. 3, I have shown one of the feed rolls 6 partially immersed in water soluble glue or gum 20 which is provided in the reservoir 8 at a predetermined level 9 and may be kept at the desired temperature and viscosity by the heater 7 which may be a gas burner or other heating element such as an electric heater and may be controlled to maintain the desired temperature by the thermostat 16. The strip of ungummed labels 17 is fed from a roll 4 in the same manner as the strip of gummed labels 3 shown in Figs. 1 and 2.

The glue, however, in the modification shown in Fig. 3, is ordinarily sufficiently moist so that the further moistening of the Cellophane to cooperate with the heat when securing the labels is not necessary.

In Figs. 1 and 2, I have shown the Cellophane as having a patch of moisture applied to its surface. The method used in Fig. 1 may be continuous while the method illustrated in Fig. 2 may be such that the Cellophane may travel intermittently while receiving the moisture on its surface.

Referring particularly to my device as shown in Fig. 1, it will be seen that as the sheet of Cellophane 12 is fed from its roll 13 and while traveling upwardly, a shield 21 is provided and so shaped and positioned that a fine spray will be confined to the exact marginal register of the label 2 which later is deposited on the patch or area of the surface of the Cellophane so moistened.

The moistened patch of Cellophane is thus confined to a limited area the size and shape of the label and so spotted or positioned that the labels will be spaced as desired on the surface of the Cellophane.

The timing of the spray will thus be seen as important. The jet 22 is opened by a solenoid 23 which is synchronized with the timing of the knife 10 which severs the labels 2 from the strip of labels 3. Both the jet and the knife are timed by the cam 24 on the shaft 25 of heater roll 11. The knife may also be operated by the solenoid 26.

The labels 2 are cut from the strip 3 by the knife 10, whereupon the heater 11 engages the label and presses it firmly against the Cellophane which is fed in a continuous sheet 12 from the roll 13. The Cellophane, with the label permanently attached to it at the desired spacing, is then fed further into the machine where it is wrapped around the cake or cut or folded or wound on another roll, or cut off and piled in a stack for other use.

The heater may be maintained at the desired temperature by the electric element 14 which may

be thermostatically controlled, or other heating means may be provided, such as gas or steam.

The heater is shown as a roll which may operate intermittently or may have only a part of its surface heated and so designed with relation to its circumference that the heater surface only may contact the label but once per revolution when traveling at a peripheral speed equal to the rate of speed of the travel of the Cellophane. The heated roll remains out of contact a substantial part of each revolution and only comes in contact with the label during that part of its revolution when its raised surface 15 engages the label after the label has been cut from the strip. The Cellophane is heated simultaneously with the label and adhesive.

The jet 22 is supplied with water or adhesive and water or such other liquid best suited to the securement of the labels to the Cellophane from the container or reservoir 18 through the suction pipe 19. Compressed air for atomizing and projecting the spray onto the sheet by the jet may be supplied to the jet by the air hose 21. Surplus moisture from the shield 21 may be drained back into the reservoir 18 by the duct 28. Adjustment of the shield and jet to insure perfect register of the moistened spot on the Cellophane sheet may be made by the adjusting screw 29 and the guides 30 which provide a means for movably securing the shield and jet to the frame 1.

Referring to Fig. 2 of the drawings, the moistening means for the Cellophane sheet is shown as a moistened absorbent pad 31 intermittently forced against the sheet 12 by the solenoid 32 and toggle 33. The solenoid is synchronized to move with the knife 10. Moisture may be supplied through a wick or other feed 34 from the reservoir 35. The pad 31 and the other parts may be of a size adapted to moisten a spot on the sheet to conform to the size of each of the labels 2. The position and register of the moist pad and other parts may be adjusted by means of the adjusting screw 36 and may be movably mounted in relation to the frame 1 by the guides 37.

It is not the purpose of this disclosure to show all of the possible modifications which may be made to secure my water soluble adhesive and the labels thus secured to a sheet of Cellophane, but rather to illustrate to those skilled in the art to which my invention pertains, how the underlying principles may be accomplished. A study of this disclosure may suggest modifications which may be used to suit my invention to numerous other applications for which it is adapted and the purpose of this detailed description is to illustrate by example rather than to limit the scope of my invention, which is set forth in the appended claims.

I claim:

1. In a device for securing labels by heat and pressure to a sheet comprising in combination means feeding the labels and sheet, means placing each label at a predetermined position on said sheet, heat pressing means securing the label to the sheet, said sheet carrying said label to said heat pressing means.

2. In a device for securing labels by heat and pressure to a sheet comprising in combination means feeding the labels and sheet, means placing each label at a predetermined position on said sheet, heat pressing means securing the label to the sheet, said sheet carrying said label to said heat pressing means, and means moistening said label before being placed on said sheet and

during transit on said sheet to said heat pressing means.

3. A label affixing machine for labels having a water soluble adhesive and a heat pressing means for uniting the labels to a continuous moving sheet of Cellophane or the like, comprising means for moistening a spot on said sheet of Cellophane while in motion to moisten the water soluble adhesive on the label when brought into register with said moistened spot and severing means placing the cut off label on said spot to be carried by and on said Cellophane sheet while in motion, said heat pressing means affixing said label to said moistened spot on said sheet while in motion.

4. A label affixing machine for labels having a water soluble adhesive and a heat pressing means for uniting the labels to a continuous moving sheet of Cellophane or the like, comprising means for moistening a spot on said sheet of Cellophane while in motion to moisten the water soluble adhesive on the label when brought into register with said moistened spot and severing means placing the cut off label on said spot to be carried by and on said Cellophane sheet while in motion, said sheet carrying said label to said heat pressing means and said heat pressing means affixing said label to said sheet while in motion.

5. A label affixing machine for labels having a water soluble adhesive and a heat pressing means for uniting the labels to a continuous moving sheet of Cellophane or the like, comprising means for moistening a spot on said sheet of Cellophane while in motion to moisten the water soluble adhesive on the label when brought into register with said moistened spot and severing means placing the cut off label on said spot to be carried by and on said Cellophane sheet while in motion, said moistening means comprising an adjustable supporting means disposed in the path of travel of said sheet and means connecting said severing means to said moistening means, whereby the register and timing of said moistening means conforms to the spot on said Cellophane at the time of severance of the label.

6. A label affixing machine for labels having a water soluble adhesive and a heat pressing means for uniting the labels to a continuous moving sheet of Cellophane or the like, comprising means for moistening a spot on said sheet of Cellophane while in motion to moisten the water soluble adhesive on the label when brought into register with said moistened spot and severing means placing the cut off label on said spot to be carried by and on said Cellophane sheet while in motion, said moistening means comprising an adjustable supporting means disposed in the path of travel of said sheet and means connecting said severing means to said moistening means, whereby the register and timing of said moistening means conforms to the spot on said Cellophane at the time of severance of the label, said adjustable supporting means comprising a reservoir and shield and a jet for spraying liquid from said reservoir.

7. A label affixing machine for labels having a water soluble adhesive and a heat pressing means for uniting the labels to a continuous moving sheet of Cellophane or the like, comprising means for moistening a spot on said sheet of Cellophane while in motion to moisten the water soluble adhesive on the label when brought into register with said moistened spot and severing means placing the cut off label on said spot to be carried by and on said Cellophane sheet while in motion, said moistening means comprising an adjustable supporting means disposed in the path of travel of said sheet and means connecting said severing means to said moistening means, whereby the register and timing of said moistening means conforms to the spot on said Cellophane at the time of severance of the label, said adjustable supporting means comprising a reservoir and a pad moistened by liquid from said reservoir and means feeding liquid from said reservoir to said pad.

8. A label affixing machine for labels having a water soluble adhesive and a heat pressing means for uniting the labels to a continuous moving sheet of Cellophane or the like, comprising means for moistening a spot on said sheet of Cellophane while in motion to moisten the water soluble adhesive on the label when brought into register with said moistened spot and severing means placing the cut off label on said spot to be carried by and on said Cellophane sheet while in motion, said moistening means comprising an adjustable supporting means disposed in the path of travel of said sheet and means connecting said severing means to said moistening means, whereby the register and timing of said moistening means conforms to the spot on said Cellophane at the time of severance of the label, said adjustable supporting means comprising a reservoir and a pad moistened by liquid from said reservoir and means feeding liquid from said reservoir to said pad, and operating means forcing said pad against a predetermined spot on said sheet of Cellophane while in motion.

9. In a process for securing labels having water soluble adhesive to a spot on the surface of a continuous moving sheet of material to which said labels will not normally adhere, first depositing the moistened label on said spot, second carrying said label on said sheet and thirdly, heat pressing said label while moist on said moving sheet of material.

10. In a process for securing labels from a roll of labels to a spot on a moving sheet of Cellophane or the like, to which labels having a water soluble adhesive will not normally adhere in which a spot on said sheet conforming to the size of the label is first moistened, then the label is cut off and deposited on the spot on the moving sheet and carried on and by the sheet and then heat pressing the label on the spot on the sheet while said spot and sheet are in motion to affix said cut off label on said spot on said sheet.

JOHN KIRBY TOMPKINS.
